Des. 189,300
Patented Nov. 22, 1960

189,300

FAN BLADE AND HUB ASSEMBLY OR SIMILAR ARTICLE

James O. McLean, Milford, Conn., assignor to General
Electric Company, a corporation of New York

Filed May 1, 1959, Ser. No. 55,744

Term of patent 14 years

(Cl. D26—7)

FIG. 1.

FIG. 2.

Fig. 3.

Fig. 4.

Fig. 1 is an elevational view of a fan blade and hub assembly embodying my new design;

Fig. 2 is a side elevational view of the fan blade and hub assembly shown in Fig. 1;

Fig. 3 is a front elevational view of the fan blade and hub assembly shown in Fig. 1; and

Fig. 4 is a cross-sectional view of one of the blades taken along the line 4—4 of Fig. 3.

The characteristic feature of my design resides in the outer portions of each blade being bent downwardly from a generally planar central portion and the minute overlapping of the corners of each blade, all as shown.

I claim:

The ornamental design for a fan blade and hub assembly or similar article, substantially as shown and described.
